SAFETY JACKET

Thomas La Maida, Cuyahoga County, Ohio; assignor to the United States of America as represented by the Secretary of the Army

Application August 29, 1946, Serial No. 693,605

4 Claims. (Cl. 2—2.5)

1

This invention relates to a safety jacket, and more particularly to a safety jacket for protecting the body of a wearer against missiles, shrapnel, and the like.

An armored safety jacket which would stop missiles, shrapnel, bullets, and the like, has long been in quest for protecting man against lethal weapons and flying missiles, especially in time of war. Though many armored jackets have been proposed, they have been invariably unsatisfactory, due either to ineffectiveness, to excessive weight, or for other reasons. It is therefore a major object of this invention to provide a safety jacket which can be worn about the body of a wearer and which jacket will afford protection against missiles of various types and at the same time be lightweight and comfortable to wear.

It is another object of this invention to provide an improved safety jacket made of a bullet-resistant material, and which is designed with hinged sections in such manner that the jacket may be expeditiously donned and doffed by a wearer.

It is a further object of this invention to provide an improved safety jacket having a back section including rigid curved portions adapted to extend over the shoulders of a wearer and in which a vertical hinged seam is provided to facilitate removal of the jacket.

Still another object of this invention is to provide an improved safety jacket having a back section including rigid curved portions adapted to extend over the shoulders of a wearer and having a horizontal hinged seam adapted to be positioned adjacent the shoulder blades of a wearer to facilitate removal of the jacket.

Still another object of this invention is to provide an improved safety jacket having a front rigid section, and a back section composed of rigid portions hinged together along a vertical seam and a horizontal seam intersecting the vertical seam approximately at the shoulder blades of a wearer, and in which some of the back portions curve forwardly and downwardly to cover the shoulders of a wearer.

It is still a further object of this invention to provide an improved safety jacket having a back section composed of hinged rigid portions, some of which portions are adapted to curve over the shoulders of a wearer and in which a front section is adapted to be suspended from the curved portions and in which strap means are provided to secure the front and back sections in cooperative relationship.

Other objects and advantages of the present

2

invention will appear in the following detailed description and particularly will be pointed out in the appended claims, reference being had to the accompanying drawings forming a part of the specification and in which:

Figure 1 is a front elevational view of the back section of the safety jacket of this invention and showing the shoulder portions and the strap means;

Figure 2 is a rear elevational view, partly broken away, of the front section of the safety jacket and showing the hook means for attaching the front section;

Figure 3 is a rear elevational view of the back section shown in Figure 1 and showing the hinged seams;

Figure 4 is a front elevational view of the safety jacket of this invention with the front and back sections secured together as for wearing;

Figure 5 is a transverse sectional view through the safety jacket taken on line 5—5 of Figure 4;

Figure 6 is a fragmentary sectional detail view taken on line 6—6 of Figure 4;

Figure 7 is a rear elevational view of the back section of a modified form of safety jacket in accordance with this invention; and

Figure 8 is a fragmentary elevational detail view of a back section of still another modified form of safety jacket in accordance with this invention and showing a modified type of hinge for joining the rigid portions.

The safety jacket of this invention is made of any suitable material that will offer resistance to flying missiles, such as bullets and/or shrapnel. For example, a plastic known as "Dorón" has been found to be suitable though other materials may be used instead.

Referring to the figures, reference numeral 1 denotes generally the back section of the safety jacket, and shown as having a centrally located vertical seam 2 and an intersecting horizontal seam 3 positioned near the top of the back section, as shown in Figure 3, so that when the jacket is worn the seam 3 will be positioned substantially adjacent the shoulder blades of a wearer. The seams 2 and 3 divide the back section into four portions, two lower portions 4 and 5 and two upper portions 6 and 7. As clearly shown in the embodiment of Figure 3, the several portions 4 to 7 inclusive, are joined together at the vertical and horizontal seams by means of the hinges 8.

The upper portions 6 and 7 curve forwardly and downwardly, as shown, so as to be adapted to cover or envelop the shoulders of a wearer.

At the forward extremities of the portions 6 and 7, straps 9 of meal, or other suitable material, are secured suitably, for a purpose to be described hereinafter. If desired, padding material 10 may be secured suitably to the portions 6 and 7 for the comfort of the wearer. However, it is within the purview of this invention to construct the safety jacket without padding material, if desired.

The front section, clearly shown in Figure 2, is composed of a unitary rigid section 11 being reinforced in any suitable manner, if desired, as for example, by a reinforcing strip 12, and having secured at its upper end a pair of hook-like members 13 which are adapted to be secured to the straps 9 in the manner shown in Figure 6 when the front section 11 is suspended from the shoulder portions 6 and 7 as in Figure 4. The hooks 13 may be secured to the front section 11 in any suitable manner as by means of rivets 14, or otherwise. When the front section 11 is suspended in the manner shown in Figure 4, the sides of the front and back sections will overlap as at 15 in Figure 5 so that protection will be afforded completely around the body of a wearer. To maintain the overlapping relationship between the back and front sections and to securely hold these parts in position on a wearer, a belt fastening means denoted generally by reference numeral 16 is provided. The belt fastening means 16 is composed of a strap 17 of any suitable material riveted as at 18, or otherwise suitably secured, to the back section, as shown in Figure 3. Preferably the strap 17 is made of a heavy elastic web material. The free ends of the strap 17 are provided with cooperating buckle members 19 and 20 of a type which may be quickly fastened and unfastened, for example one having a tongue 21 on one buckle member adapted to fit into a slot 22 on the other buckle member. As shown in Figure 4, the free ends of the strap 17 are adapted to encircle the front section 11 for buckling as shown in Figure 4 to hold the parts in wearing position. In order to adapt the safety jacket for various girths, the strap is provided with a conventional adjusting means 23 for adjusting its length. Also, the overlap at 15 is made preferably substantial so as to insure an overlap for wearers of large girth.

In Figure 7 a modified form of back section is illustrated differing from the back section shown in Figure 3 primarily in the shape of the portions 4', 5', 6', and 7' and in the arrangement and number of the hinges 8'. The operation of the back section of Figure 7 is the same as that of Figure 3 and also may be used with the front section 11.

In Figure 8 there is illustrated a portion of still another modified back section provided with a different type of hinge means from that shown in Figures 3 and 7. The Figure 8 embodiment utilizes the rings 24 passing through openings 25 in the portions 4'', 5'', 6'', and 7'' for joining the several portions of the back section. This form of hinge provides for a readily flexible seam constituting a relatively loose connection between the portions so as to permit pivotal movement of the portions 4'', 5'', 6'', and 7'' simultaneously along both the vertical and horizontal seams. This double pivoting about both seams simultaneously, due primarily to the loose connection of the hinge means, further facilitates expeditious donning and doffing of the jacket, as described hereinafter.

In operation, in donning the safety jacket, the wearer first places the back section in position

with the curved portions 6 and 7 resting on the shoulders. In placing the back section in this manner the rigid portions thereof may be moved about their pivots at the seams to facilitate placing the section in position. Then the front section 11 is suspended from the shoulder portions 6 and 7 with the hooks 13 engaging the straps 9. Then the belt fastening means 16 is carried forwardly and buckled to encircle the front section 11 and hold same in cooperative relationship with the back section.

Now when it is desired to remove the safety jacket of this invention, the steps are reversed. First the belt 16 is unbuckled, then the front section 11 is lifted and then the back section is flexed backwardly about the vertical and/or the horizontal seams to quickly disengage the back and shoulder portions from the body. The construction of the safety jacket of this invention is such that the removal of the jacket from the body of a wearer may be performed effectively in the shortest possible time. More specifically, it is to be noted that no buttons or cumbersome securing means are utilized to hold the sections of the jacket together, the buckle may be quickly separated merely by sliding buckle portion 19 relatively to buckle portion 20 to disengage the tongue 21 from the slot 22. Similarly, the front section 11 is removed by merely a lifting operation. The back section may be quickly removed merely by engaging the front extremities of the portions 6 and 7 with the thumbs and then by a slight tilting upwardly and outwardly, the back section will flex at one or both of the seams 2 and 3 and quickly become disengaged from the body of the wearer. In removing the safety jacket of this invention, it has been shown that the jacket can be removed in a matter of a second or two. The lifting motion to remove the front section 11 and applying the thumbs to the shoulder portions 6 and 7 for removing the back section may be performed in one sweeping motion during which the front section 11 is permitted to drop as soon as disengaged.

It is thus evident that a safety jacket has been provided which will give a wearer adequate protection against missiles of various types, which is lightweight, can be worn without causing the wearer to feel tired or uncomfortable, which is properly balanced on the shoulders of a wearer, and which can be quickly donned and quickly discarded in a matter of a few seconds. It is pointed out that having the horizontal seam 3 as shown, where it will be adapted to be positioned immediately adjacent the shoulder blades of a wearer, constitutes an essential feature of this invention, especially in combination with the vertical seam 2. It is only through the use of these seams positioned, as shown, that the curved upper portions 6 and 7 engaging the shoulders can be quickly released from the shoulders without tugging and pulling on the jacket. The shoulder portions 6 and 7 will tilt upwardly and backwardly due to the horizontal seam 3 and will also tilt somewhat outwardly to the sides due to the vertical seam 2. Also, it is to be noted that though a quickly removable jacket has been provided, the rigid bullet-resistant character of the jacket has not been sacrificed.

In use when the jacket is worn the brunt of the weight of the jacket is carried by the shoulders of the wearer and for this reason, the padding 10 will be found to be of advantage in uniformly distributing the weight of the jacket on the shoulders of the wearer irrespective of the shape of

the shoulders and give the wearer a comfortable feeling in any position assumed by the wearer. Also in use, the jacket can be worn either under or over clothing.

Though certain shapes for the front and back sections are described and illustrated, it is within the purview of this invention to utilize other shapes for either or both of the front or back sections, or for the several portions of the back section. Also, if desired the shoulder portions 6 10 and 7 can be made wider than illustrated to give greater shoulder protection.

In manufacture, the sections of the jacket can be molded to proper size, or can be cut from larger sheets. The front section 11, as illustrated, is 15 cut long and in a V-shape to extend as far as the groin, but it is also within the purview of this invention to make the front section shorter to adapt it for wear under a coat. Also other styles for the front section can be used. Also, the front section can be omitted, if desired.

While the invention has been described in more or less detail, it is not to be limited thereby, as changes may be made in the form, arrangement, and construction of parts, and equivalents may be substituted, without departing from the spirit and scope of the invention as claimed, the forms hereinbefore described being merely preferred embodiments thereof.

I claim:

1. A safety jacket for protecting the body of a wearer, comprising a back portion and a front portion, curved extensions on the back portion adapted to extend over the shoulders of the wearer, horizontally extending straps on the forward ends of the curved extensions, and downwardly directed hooks on the upper edge of the front portion adapted to engage said straps.

2. A safety jacket for protecting the body of a wearer, comprising a back portion consisting of 40 upper and lower sections hingedly connected by horizontal hinges at approximately the shoulder

blades, said sections each consisting of two panels having adjacent vertical edges, the upper panels being provided with curved portions adapted to extend over the shoulders of the wearer, and hinge connections between the adjacent vertical edges of the upper and lower panels.

3. A safety jacket for protecting the body of a wearer, comprising a front portion and a back portion, said back portion consisting of upper and lower sections hingedly connected by horizontal hinges at approximately the shoulder blades, said sections each consisting of two panels having adjacent vertical edges, the upper panels being provided with curved portions adapted to extend over the shoulders of the wearer, hinge connections between the adjacent vertical edges of the upper and lower panels, and slidably engageable connections on the forward edges of the curved portions and the upper end of the front portion.

4. A safety jacket for protecting the body of a wearer, comprising a back portion, curved extensions on the back portion adapted to extend over the shoulders of the wearer, a plate-like front portion overlapping said extensions, and vertically-slidable engageable and disengageable connections between the extensions and the plate-like front portion, whereby the front portion need be moved in an upward direction only in order to be detached from the back portion.
